TROPHY BASE

Alexander Pistey, 140 Hurd St., Bridgeport, Conn.

Filed Dec. 30, 1963, Ser. No. 77,951

Term of patent 7 years

(Cl. D29—28)

FIG. 1.

FIG. 2.

FIG. 3.

FIG. 4.

FIG. 2 is a side elevational view thereof;

FIG. 3 is a top plan view thereof; and

FIG. 4 is a sectional view taken on line 4—4 of FIG. 1.

I claim:

The ornamental design for a trophy base, substantially as shown.
